The ornamental design for a female patient garment, as shown.

DESCRIPTION

FIG. 1 is a front view of a garment showing my new design, with portions of a front panel portion of the garment shown folded over to show portions of a rear panel;

FIG. 2 is a rear view of said garment;

FIG. 3 is a left-side view of said garment;

FIG. 4 is a right-side view of said garment;

FIG. 5 is a top view of said garment; and,

FIG. 6 is a bottom view of said garment.

The front of the garment is a mirror image of the rear of the garment with the exception of the pocket.
